L. E. GOLLY

VACUUM PNEUMATIC HAMMER

Filed Oct. 18, 1921

Louis E. Golly Inventor
By his Attorney

Clarence G. Campbell

UNITED STATES PATENT OFFICE.

LOUIS E. GOLLY, OF BROOKLYN, NEW YORK, ASSIGNOR TO JAMES C. CAMPBELL, OF NEW YORK, N. Y.

VACUUM PNEUMATIC HAMMER.

Application filed October 18, 1921. Serial No. 508,534.

To all whom it may concern:

Be it known that I, Louis E. GOLLY, a citizen of the United States, residing at 665 Bushwick Avenue, in the borough of

5 Brooklyn, in the county of Kings, city and State of New York, have invented certain new and useful Improvements in Vacuum Pneumatic Hammers, of which the following is a specification.

10 This invention relates to a vacuum pneumatic hammer, and more particularly to the adaptation and arrangement of the parts, as will be more fully hereinafter pointed out.

15 The object of the invention is to provide a construction which is simple and efficient in operation for pneumatically operating a hammer by the compression and rarefying of air through the action of a piston operating in a cylinder or tube.

20 A further object of the invention is to provide a device or tool of the character referred to which can be manufactured economically and which is capable of easy and 25 ready application to its work and which can be readily controlled in its operation.

25 Referring to the accompanying drawings Figure 1 is a longitudinal section of my device; Figure 2 is a longitudinal section of the outer casing on the lines 2-2 of Figure 3; Figure 3 is an end view of the outer casing looking in at the right of Figure 2; Figure 4 is an end view of Figure 5 looking in at the left; Figure 5 is a section 35 of the tool holder end of my device; and Figure 6 is an end view of Figure 5 looking in at the right.

30 In the drawings 7 is an outer casing being internally threaded at 8 so that it is adapted to screw over a similar external threading of a driver housing 9, and a cylinder 10 is so constructed and mounted in the outer casing 7 that it can oscillate longitudinally freely therein. The cylinder 10 has a shoulder 11 which is adapted to engage a shoulder 12 of the outer casing 7, so as to limit the downward motion of the cylinder 10. The cylinder 10 is externally threaded at 13 so that it is adapted to receive the internal threading of a tool holder 14 so that the tool holder 14 is thereby rigidly secured to the cylinder 10. A spiral spring 15 is mounted over the cylinder 10 so that it bears at the lower end on the tool holder 14 at the 45 shoulder 16 and bears at the upper end on

the shoulder 17 of the outer casing 7, so that the cylinder 10 and tool holder 14 which is rigidly connected thereto are always under spring tension against the outer casing 7.

40 The driver housing 9 contains a driving plate which is driven by a source of power, neither of which are shown herein, but said driving plate has a cylindrical bearing eccentric 21 which is adapted to have mounted thereover an upper cylindrical member 23 of a plunger arm 22 so as to turn freely thereon. A driven plate 18 has an eccentric pin 19 which is adapted to fit into the cylindrical member 21 and a counter balance 20 is rigidly secured to said plate 18 and rotates therewith. The lower end of said plunger arm 22 ends in a ball 44 adapted to fit into a socket 24 of a plunger 25 which is adapted to slide longitudinally on the inside of the cylinder 10. The lower end of 45 the plunger 25 terminates in a cylindrical air cushion pocket 26 which is constructed and adapted to receive a head member 27 of a hammer 28 which is also adapted to slide longitudinally on the inside of the cylinder 50 55 60 65 70 75 80

70 The upper end of the driver housing terminates in a handle 29 of usual construction, and the lower end of the tool holder 14 has a mouth 30 adapted to receive the upper 75 end of a tool, such as a chisel or other similar tool, which end will slide into the longitudinal opening 31 of the tool holder 14.

75 The outer casing 7 has an air port 32 which also runs through the driver housing 9 and air ports 33 and 34 opposite each other near the lower end of said casing. The casing 7 also has on the inside thereof cylindrical cut outs or air passages 35, 36, and 37. Said casing 7 also has longitudinal borings 38 which connect the cylindrical air passages 36 and 37, and further longitudinal borings 39 which connect the cylindrical air passage 37 with the outer air through the base of the casing 7. The tool holder 100 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920

passages 41 with the outer air. The cylinder 10 also has air ports 45 and 46 which in the lower or normal position of the cylinder 10 register with the cylindrical borings 37 and 36, respectively.

5 The operation of my device is as follows: A hammer, chisel, or other suitable tool 43 is mounted in the usual way in the opening 30. The motor switch, which is not 10 shown, is then turned on thereby rotating the driven plate 18 and the counterbalance 20 which travels therewith. The eccentric pin 19 and bearing 21 are thereby rotated eccentrically so as to carry the upper cylindrical member 23 and the connecting parts 22, 44 and plunger 25 back and forth on the inside of the cylinder 10, because of such eccentric rotation. The hammer 28 normally rests in the base of the inside of the cylinder 10, but as the operator presses down on the 15 tool 43 in order to cause the tool to operate as desired the tool holder 14 is thereby pushed up against the spring 15 which carries the cylinder 10 therewith so that the 20 ports 45 are thereby pushed out of alignment with the cylindrical boring 37, and the rotation of the plunger 25 thereby causes a suction or vacuum on its upward motion which draws the hammer 28 up until the 25 head 27 pushes part way into the cylindrical pocket 26 of the plunger 25 in which an air cushion is formed so that 27 does not actually contact with the head of the pocket. The hammer 28 is then pushed downwardly 30 by the downward stroke of the plunger 25 and hits the head of the tool 43 which projects sufficiently from the cylindrical opening 31, so that the hammer 28 can come into full contact therewith on the downward 35 stroke. The air which would otherwise be compressed under the downward stroke of the hammer 28 escapes through the ports 42 and the cylindrical boring 40 into the longitudinal air passages 41. As the operator 40 pushes down further on the tool thereby compressing the spring 15, the cylinder 10 is further raised so that air ports 46 are also thrown out of engagement with cylindrical borings 36 thereby increasing the 45 vacuum above the hammer 28 which will cause the hammer 28 to go further up on the up stroke, so that on the downward stroke the hammer 28 will hit the head of the tool 43 harder, thereby operating the tool 43 in a 50 more forceful manner. Port 32 serves to maintain atmospheric pressure on the inside of the driver housing 9.

I claim:

1. In a vacuum power hammer the combination of a power driven eccentric, a 60 plunger having an air cushion pocket and adapted to slide in a cylinder longitudinally movable in an outer casing having air ports, cylindrical cutouts and longitudinal 65 borings connecting the lower pair of said

cutouts, a tool holder separately connected to the lower end of said cylinder, a hammer adapted to cushion in said plunger air pocket, air ports in said cylinder normally registering with said cylindrical cutouts in 70 said outer casing, and means for interrupting such registration.

2. In a vacuum power hammer the combination of a power driven eccentric, an outer casing having air ports, cylindrical cutouts and longitudinal borings connecting said lower pair of said cutouts, a longitudinally movable cylinder mounted in said casing and limited thereby in its downward movement, a tool holder separably secured 75 to said cylinder and under spring tension against said outer casing, a plunger having an air cushion pocket, a hammer adapted to slide in said cylinder and cushion in said pocket, and said cylinder cooperating with 80 said casing for interrupting the maintaining of atmospheric pressure between said hammer and said plunger.

3. In a vacuum power hammer the combination of a power driven eccentric mounted in a housing, an outer casing secured to said housing and having air ports at the upper and lower ends, three cylindrical cutouts and a longitudinal boring connecting the two lower cutouts, a longitudinally movable cylinder mounted in said casing, a tool holder connected with one end of said cylinder, a plunger operated by said eccentric and having an air cushion pocket, means for actuating said plunger, a reciprocatory hammer adapted to slide in said cylinder having a head adapted to cushion in the air pocket of the plunger, said cylinder having air ports adapted to register with said cylindrical cutouts of said casing in the non-operative position and said air ports not registering with the cylindrical cutouts when the tool holder and cylinder are pushed upwardly to the operative position.

4. In a vacuum power hammer the combination of a power driven eccentric, a plunger having an air cushion pocket and adapted to slide in a cylinder movable longitudinally in an outer casing, said outer casing having air ports, cylindrical cutouts and longitudinal borings connecting the lower pair of said cutouts, a hammer having a head adapted to cushion in said plunger air pocket, air ports in said cylinder normally registering with the cylindrical cutouts in 115 said outer casing, means for interrupting such registration, and means for operating said plunger comprising said eccentric having a driver plate and a driven plate, a counterbalance secured to each, and a connecting arm eccentrically connecting said plates to said plunger.

5. In a vacuum power hammer the combination of an outer casing having air ports, cylindrical cutouts and longitudinal borings 120

connecting the lower pair of said cutouts, a longitudinally movable cylinder mounted therein and limited thereby in its downward movement and having air ports, a tool holder separately secured to said cylinder and under constant spring tension against said outer casing, a plunger and hammer adapted to slide in said cylinder, means for interrupting the maintaining of atmospheric pressure between the hammer and plunger, consisting of said air ports, cylindrical cutouts and longitudinal borings, means for operating said plunger consisting of a driver plate and a driven plate, a counter-balance secured to each, and a connecting arm eccentrically connecting said plates to said plunger.

6. In a vacuum power hammer the combi-

nation of an outer casing having air ports, cylindrical cutouts and longitudinal borings connecting said lower pair of cutouts, a cylinder with a tool holder separably connected to one end of said cylinder and air ports in said cylinder adapted to register with the air ports of said outer casing in one position of the oscillation and out of registration in the other, a reciprocatory plunger in said cylinder having an air cushion pocket, means for actuating said plunger consisting of a driver and a driven plate, a counter-balance secured to each and a connecting arm eccentrically connecting said plates to said plunger.

In testimony whereof I affix my signature.

LOUIS E. GOLLY.
